UNITED STATES PATENT OFFICE.

JAMES I. AYER, OF CAMBRIDGE, MASSACHUSETTS, ASSIGNOR TO SIMPLEX ELECTRIC HEATING COMPANY, OF CAMBRIDGE, MASSACHUSETTS, A CORPORATION OF MASSACHUSETTS.

ELECTRIC-FLAT-IRON STAND.

1,116,004.

Specification of Letters Patent.

Patented Nov. 3, 1914.

Application filed July 16, 1910. Serial No. 572,229.

To all whom it may concern:

Be it known that I, JAMES I. AYER, a citizen of the United States, residing at Cambridge, in the county of Middlesex and State 5 of Massachusetts, have invented an Improvement in Electric-Flat-Iron Stands, of which the following description, in connection with the accompanying drawings, is a specification, like letters on the drawings 10 representing like parts.

My invention provides an attachment for a usual flatiron stand whereby it is made convertible into a support for a heating apparatus, in which the flatiron itself constitutes said heating apparatus. To this end I combine a suitable stand with a detachable and preferably spring frame adapted to support an electric flatiron in bottom-upward position to receive on its then flat 20 top side a cup, pot, or any other device whose contents it is desired to heat. When the flatiron and stand are to be used in the ordinary way, said frame is simply detached from the stand or removed out of the way, 25 leaving the latter in usual condition to receive the flatiron right side up.

In the accompanying drawings, in which I have shown a preferred embodiment of my invention, Figure 1 is a perspective view thereof; Fig. 2 shows the same in side elevation with a flatiron in operative position thereon; and Fig. 3 is an end elevation indicating the flatiron by dotted lines.

The general shape, construction, and arrangement of the stand proper may be of any usual or preferred kind, being herein shown as comprising a base 1, preferably of slate, and a flatiron support 2, preferably of metal, shown as held above said base 35 by spacing posts 3 so as to provide a cooling air space between the base and support, the latter having a more or less continuous flange 4 at its edges for keeping the iron in position when placed thereon right side up. As herein shown in the preferred embodiment of my invention, I provide a slot 5 adjacent the forward end of the support 2 and notches 6 in the rear end thereof to receive a frame 7. This frame is herein

shown as made of stiff spring wire bent into 50 U-shape at its middle to form an approximately vertical upright portion, standard, or leg, whose bottom end 8 is slightly curved as clearly shown in Fig. 3 to rest upon the base 1 when said leg is shoved down into 55 place through the slot 5, said upright portion, standard, or leg extending thence upward in two approximately parallel members 9 slightly deflected from each other adjacent their upper ends 10. From the 60 upper ends of these leg members at 11, the frame extends in two approximately horizontal top-portions or supports 12 to a point 13 preferably over the rear end of the support 2, whence the free ends of the wire 65 are bent downwardly to constitute an upright portion, standard, or leg, corresponding to the somewhat similar upright portion at the opposite end already described and also having deflected upper ends 14 70 and approximately parallel portions 15 corresponding to the parts 10 and 9 previously described. The lower extremities of the wire are bent away from each other to constitute supporting feet 16. A usual electric flatiron 17 is shown in operative position 75 on the frame provided with usual current-receiving posts 18 for receiving the slide connector or socket piece in well known manner, my invention being particularly 80 adapted to electric flatirons, although not limited thereto, as it will perform its useful functions in connection with any flatiron which contains its own heating apparatus.

When the usual stand comprising the parts 1 2 is to be used in the usual manner, the frame is omitted, so that the flatiron may be placed right side up directly on top of the part 2 and removed therefrom in 85 well known manner. When however it is desired to support the flatiron bottom upward as shown in Figs. 2 and 3 so as to use the flatiron not as a smoothing iron but as a heat transmitting body for heating 90 whatever may be placed upon its smooth top surface, the frame is put in place in rigidly interlocked relation to the part 2,

its rear end being snapped into the notches 6 and then its front U-shaped leg sprung into the holding slot 5. To facilitate the entrance of said leg into said slot, the rear 5 wall of the slot is hollowed or curved as indicated at 19, and the ends of the slot extend rearwardly at 20 to practically grasp the upright portions of the leg and therefore aid in the stability of the frame.

10 In use, it being supposed that the stand proper has been in use for supporting the flatiron right side up and it is desired to convert the apparatus into a heating device as shown in Figs. 2 and 3, the two members 15 of the rear leg or standard of the frame are pinched together from their normal dotted line position Fig. 1 and snapped into the notches 6 as shown in full lines Fig. 1, so that their feet 16 rest on the base 1 as shown in full lines in all the figures, and then the front U-shaped end 8 is pushed slightly forward from its dotted line position Fig. 1 and at the same time crowded downward against the hollowed or curved end 19 of the slot 5, 20 which facilitates the springing forward and moving downward of said front leg or standard as the operator presses hard down upon the frame, the result being that said front leg or standard of the frame goes forward and downward at once without requiring any skill or care on the part of the operator, and as soon as the end 8 is fully within the slot 5 its upright portions snap back into the notches 20, thereby coöperating with the 25 notches 6 in practically locking the frame rigidly in place. The dotted lines in Fig. 1 show the normal shape and position of the frame when it is placed on the parts 1 and 2 ready to be interlocked with part 2, before 30 any attempt has been made to put it into interlocked position, and the full line position of the frame as shown in Fig. 1 indicates its operative position as a part of the supporting stand when interlocked with the part 2 and supported by the parts 2 and 1. Having put the stand together in the manner just described, the flatiron is turned bottom side up and its handle 21 is forced down between the flaring spring portions of the 35 frame which yield to permit the flatiron to descend until its weight is supported on the horizontal portions 12 as shown in Figs. 2 and 3. The flaring upper portions 10 and 14 of the two legs or end standards coöperate in receiving and directing the handle downward and at the same time facilitate the wedging action of the handle in separating the spring members from the full line position Fig. 3 to the dotted line position. 40 When the handle is fully down, it is between the approximately parallel portions 9 and 15, which pinch the same with sufficient pressure to hold it laterally immovable. The end standards or legs of the frame are lo-

cated at such a distance apart as corresponds 45 to the usual reduced portion 22 of the flat-iron handle, so that this pinching engagement of said standards or legs with the handle, not only prevents the lateral movement 50 of the handle but also coöperates with these reduced portions of the handle to prevent any possible endwise movement of the flat-iron with relation to the frame. Having put the flatiron in position as shown in Figs. 2 and 3, the connector of the current conductor is slid onto the terminals 18, thereafter quickly heating the flatiron, and, through the latter, heating whatever cooking utensil or other device may be placed 55 thereon.

It will be understood that my invention is capable of a wide variety of embodiments, as will be more fully apparent from the appended claims.

Having described my invention, what I claim as new and desire to secure by Letters Patent is,

1. In combination, a flatiron stand proper adapted to support a flatiron in normal upright position and a support adapted to be 90 removably engaged with said stand for holding the flatiron bottom upward and with a space for the reception of the handle thereof, said support being formed of rod or wire stock and having its ends formed as angular 95 spring arms arranged to interengage with the stand at laterally separated points for yieldingly holding the parts together with an elastic distortion of said ends.

2. In combination, a flatiron stand proper 100 adapted to support a flatiron in normal upright position and a support adapted to be removably engaged with said stand for holding the flatiron bottom upward with a space 105 for the reception of the handle thereof, said support being formed of rod or wire stock with a central portion formed as a bent loop to engage the stand at one end portion thereof, the ends of said rod being formed as angular spring arms to engage the other-end portion of the stand at laterally separated 110 points and arranged to hold the parts yieldingly together by elastic pressure.

3. A flatiron stand, comprising a lower part containing a slot at one end and notches 115 at its other end, and an upper part containing a leg at one end adapted to enter and lock into said slot, and spring members at its other end adapted to be sprung into locking position in said notches, said upper part 120 having a shape to receive and support a flatiron in bottom upward position.

4. A flatiron stand, comprising a lower part adapted to receive a flatiron in upright position, and an upper part detachably supported by said lower part for receiving a flatiron in inverted position, said upper part 125 having end legs made of wire, one leg being

U-shaped at its lower end, and the other leg being composed of two upright spring members terminating at their lower ends in laterally bent feet, said two legs being shaped 5 to embrace portions of said lower part under sufficient tension with relation to the latter to hold them locked in place.

In testimony whereof, I have signed my name to this specification, in the presence of two subscribing witnesses.

JAMES I. AYER.
